(57) CLAIM

The ornamental design for ceiling fan, as shown and described.

DESCRIPTION

FIG. 1 is a bottom perspective view of the ceiling fan showing my design;

FIG. 2 is a side elevational view thereof;

FIG. 3 is a side elevational view thereof;

FIG. 4 is a side elevational view thereof;

FIG. 5 is a side elevational view thereof;

FIG. 6 is a top plan view thereof; and,

FIG. 7 is a bottom plan view thereof.

The support rod has been shown broken away in FIGS. 1–6 and the ceiling fan blades have been shown broken away in FIGS. 1–7 to indicate indeterminate length.
